RUBBER MAT

Paul Clark, Fremont, Ohio, assignor to Fremont
Rubber Company, Fremont, Ohio, a corpora-
tion of Ohio

Application July 25, 1949, Serial No. 4,131

Term of patent 14 years

(Cl. D9—6)

To all whom it may concern:

Be it known that I, Paul Clark, a citizen of the United States and resident of Fremont, county of Sandusky, State of Ohio, have invented a new, original, and ornamental Design for a Rubber Mat, of which the following is a specification, reference being had to the accompanying drawing, forming a part thereof.

In the drawings, Fig. 1 is a plan view of a rubber mat embodying my new design, Fig. 2 is an end view taken across the width thereof from right to left in Fig. 1, and Fig. 3 is a side view of a portion of the mat shown in Fig. 1.

I claim:

The ornamental design for a rubber mat, substantially as shown.

PAUL CLARK.
